Primary Examiner — Jack Reickel*Assistant Examiner* — Bobby W Jones II(74) *Attorney, Agent, or Firm* — Edell, Shapiro & Finn, LLC(57) **CLAIM**

The ornamental design for a filter indicator, as shown and described.

DESCRIPTION

FIG. 1 is a perspective view of a filter indicator showing the new design;

FIG. 2 is a top view thereof;

FIG. 3 is a bottom view thereof;

FIG. 4 is a left side view thereof;

FIG. 5 is a right side view thereof;

FIG. 6 is a front view thereof; and,

FIG. 7 is a back view thereof.

The broken line showing of a filter indicator is included for the purpose of illustrating portions of the article and forms no part of the claimed design.

1 Claim, 4 Drawing Sheets(56)
